THE NORRIS PETERS CO., PHOTO-LITHO., WASHINGTON, D. C.

UNITED STATES PATENT OFFICE.

AUGUSTUS GOULD, OF NORWICH, CONNECTICUT, ASSIGNOR TO WILLIAM A. BREED, OF NORWICH, CONNECTICUT.

STOP-MOTION FOR CUTLERY-GRINDING MACHINES.

SPECIFICATION forming part of Letters Patent No. 708,136, dated September 2, 1902.

Application filed January 10, 1902. Serial No. 89,171. (No model.)

To all whom it may concern:

Be it known that I, AUGUSTUS GOULD, a citizen of the United States, residing at Norwich, in the county of New London and State 5 of Connecticut, have invented certain new and useful Improvements in Stop-Motions for Cutlery-Grinding Machines, of which the following is a full, clear, and exact description.

This invention relates to a class of mechanisms commonly known as "stop-motions," which mechanisms in different forms are applicable to various classes of machinery and serve to accomplish automatically the stopping of such machinery upon the completion 15 of certain prescribed operations.

The object of this present invention is to provide a stop-motion applicable particularly to cutlery-grinding machinery in which a reciprocating work-table is provided, and the 20 said invention is therefore shown and described in connection with such machinery.

To assist in explaining this invention, the accompanying sheets of drawings have been provided, illustrating the same, as follows:

25 Figure 1 is an elevation of the upper portion of a grinding-machine fitted up with the newly-invented stop-motion. Fig. 2 is a side elevation of the knife carriage or table of the said machine and of the stop-motion as seen 30 from the left hand of Fig. 1. Fig. 3 is a plan view, on a somewhat-enlarged scale, of the said table and stop-motion. Fig. 4 is a side elevation of a portion of the said table and of a certain element of the stop-motion's 35 mechanism that is secured thereto. Fig. 5 shows detached a portion of the mechanism comprising the newly-invented stop-motion.

Referring to the drawings, the letter *a* denotes the upper portion of the stand of a 40 grinding-machine, and *a'* a bracket secured thereto, supporting the bearings *b* of a shaft *c*, which latter bears fast and loose pulleys *c'* and *c''*, and at one end within a suitable casing (denoted by *a''*) the said shaft *c* bears the usual 45 grinding-wheel *d*. The cutlery to be ground is introduced to the face of the grinding-wheel *d*, and to accomplish this end such cutlery is secured to a horizontally-reciprocating table or carriage actuated by suitable 50 mechanism so as to travel toward and away from the said grinding-wheel.

The reference-letter *a*³ denotes a bracket secured to the frame *a*, bearing thereon a block *e*, upon which latter the work-supporting carriage or table *f* is mounted and adapted to 55 travel reciprocally. The reciprocatory travel of the carriage *f* upon the block *e* is accomplished by means of mechanism located principally within the said block, and thus hidden from view and protected from dirt, and as such 60 mechanism forms the subject of a separate application and is in no way a part of this invention it is thought necessary to illustrate and describe only the exterior elements of said mechanism. Describing now the said exterior 65 elements, the reference-letters *g* *g'* denote the ends of two parallel screws which project through the end of the block *e* and bear, respectively, gears *h* *h'*, adjacent to the outer face of the said end of the block *e*. The gears 70 *h* *h'* are in mesh with each other, and the former is also in mesh with a spur-gear *h*², mounted upon a stud *h*³, projecting from the block *e*, which said spur-gear *h*² has secured thereto one of a pair of bevel-gears *h*⁴. The companion gear of the said pair of gears is mounted upon a shaft *k*, supported in a bearing *m'*, formed in a casting *m*, secured to the block *e*, which said shaft bears also a driving-pulley *k*². Upon the rotation of the driving-pulley *k*² motion is imparted from its shaft *k* 80 through the pair of bevel-gears *h*⁴ to the spur-gear *h*² and from the latter to the gears *h* *h'* and the screws *g* *g'*, upon which latter the gears *h* and *h'* are respectively mounted. The 85 rotation of the screws *g* and *g'* sets in operation the before-mentioned mechanism within the bed *e*, whereby the table *f* is actuated to travel reciprocally upon the said bed.

The reference-letter *u* denotes a knife 90 which is secured to the side of the carriage *f*, as seen in Fig. 1 and as shown in dotted lines in Fig. 2. The driving mechanism of the carriage is so arranged as to cause the latter to carry the knife into engagement with 95 the emery-wheel *d*, the position of said knife and the extent of travel of the carriage being such that the knife-blade will be ground from its outer end to the bolster.

The particular office of the newly-invented 100 stop-motion is to check the reciprocatory travel of the carriage *f* upon the completion

of each grinding operation—that is to say, upon the return of the carriage to its starting position—to permit the removal of the ground knife-blank and the insertion of an unground blank. Describing now particularly the said stop-motion, the driving-pulley k^2 instead of being fixedly secured to the shaft k is loosely mounted thereon and is adapted to be secured to the said shaft by means of clutch mechanism intermediate the pulley k^2 and the bearing m' .

The reference-letter o denotes a collar mounted on and secured to the shaft k and serving, with the hub of the bevel-gear h^4 of said shaft, to prevent endwise movement of the latter in its bearing m' . The fixed collar o also forms the fixed section of a clutch, the companion or slidable section of which is an extension o' of the hub of the driving-pulley k^2 . The confronting faces of the fixed and movable clutch-sections o o' are each provided with pins o^2 , which pins when the slid-able clutch-section is held adjacent the fixed section are adapted to engage each other to cause the said fixed clutch-section to revolve in unison with the movable section and with the driving-pulley k^2 . A sleeve p is secured to the end of the shaft k , which sleeve is counterbored from its end adjacent the wheel k^2 to provide a chamber p' , which receives a spring p^2 , that encircles the shaft k , and whose opposite ends abut, respectively, the bottom of the chamber p' and the hub of the wheel k^2 . The spring p^2 acts normally to hold the slid-able clutch-section o' in close proximity to the fixed clutch-section o , causing the pins o^2 to engage each other, thus locking the clutch-sections o o' together and locking the pulley k^2 to the shaft k .

The reference-letter m^2 denotes a bearing in the casting m , extending parallel with the bearing m' and provided for the reception of a bolt q , which is capable of limited endwise movement in the said bearing m^2 . The bolt q at its end adjacent the wheel k^2 carries a fork q' , that is adapted to engage an annular groove o^3 in the slid-able clutch-section o' , and the opposite end of said bolt q is beveled, as at q^2 , for a purpose to be explained. Ad-justably bolted to the side of the carriage f is a plate s , having a hinged extension s' , whose edge at its free end is beveled, as at s^2 . The said beveled end s^2 of the bolt q (when the said bolt is in its inner normal position) lies in the path of the beveled end s^2 of the hinged portion s' of the plate s , and said beveled edge s^2 in the rearward travel of the carriage f is adapted to engage the beveled end q^2 of the bolt q to force the latter outward and sepa-rate the clutch-sections o o' . When the stop-motion is in position upon the grinding-machine, the beveled edge s^2 is adapted to thus engage the bolt q to separate the clutch-sections just at the completion of the rearward travel of the carriage e .

Assuming that the various elements of the

stop-motion mechanism are properly in position and that a knife-blank is in position to be ground, the carriage f travels in the direction of the arrow in Fig. 2 until said carriage reaches approximately the position shown in dotted lines in said figure. The carriage f is then automatically reversed and travels in the direction of the arrow of Fig. 3 and opposite that of the arrow in Fig. 2. Just before the carriage f reaches its rear-most position (the position shown in dotted lines in Fig. 3) the beveled edge s^2 of the hinged plate s' engages the beveled end q^2 of the bolt q , causing the bolt end to ride upward on the said beveled edge s^2 and onto the plate s' , thus sliding the said bolt in the bearing m^2 and through the fork q' separating the slid-able clutch-section o' from the fixed section o , (see Fig. 5,) operating against the force of the spring p^2 , the just-mentioned movable parts and the driving-wheel k^2 being changed from their positions shown in full lines to those shown in dotted lines in Fig. 3. Upon the several movable elements assuming their re-spective positions (shown in dotted lines) the clutch-sections o o' will have become discon-nected and the travel of the carriage will of ne-cessity cease. The finished knife-blank may now be removed from the carriage and an un-ground blank placed in position, after which the carriage is again set in motion by simply rocking the hinged plate portion s' upward from and out of contact with the bolt end q^2 , (Fig. 4, dotted lines,) thus permitting the spiral spring p^2 to return the several movable elements to their normal positions, the clutch-sections o o' becoming again locked and the driving of the carriage again effected. As the carriage f again travels forward the hinged plate-section s' rides upon the end of the bolt q until the latter passes from beneath said hinged section, when the latter is allowed to drop by gravity to its normal position.

While the newly-invented stop-motion is shown and described as applied to cutlery-grinding machinery, it is not to be considered as confined to such use, as it would be equally applicable to other classes of machinery em-bodying a reciprocating table driven in sub-stantially the same manner as here shown.

Having thus described my invention, I claim—

In combination with a shaft k , a constantly-rotating pulley loosely mounted on said shaft, clutch mechanism connecting the said shaft and pulley, a reciprocating table, and means for disconnecting the said clutch consisting of a rod q , fork q' , and a hinged latch carried by the said reciprocating table, substantially as herein specified.

Signed at Norwich, Connecticut, this 23d day of December, 1901.

AUGUSTUS GOULD.
